UNITED STATES PATENT OFFICE.

TALBOT G. MARTIN, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

TELEPHONE-EXCHANGE SYSTEM.

1,185,522.

Specification of Letters Patent.

Patented May 30, 1916.

Application filed May 29, 1906, Serial No. 319,255. Renewed October 25, 1915. Serial No. 57,868.

To all whom it may concern:

Be it known that I, TALBOT G. MARTIN, a citizen of the United States of America, and resident of Chicago, Cook county, Illinois, 5 have invented a certain new and useful Improvement in Telephone-Exchange Systems, of which the following is a specification.

My invention relates to telephone systems in general, but more particularly to automatic or semi-automatic telephone exchange system, and especially to systems in which two or more exchanges or central stations are connected by one or more trunk-lines, thereby affording telephone service between 15 subscribers of different exchanges.

Generally stated, the object of my invention is the provision of an improved and highly efficient telephone exchange system.

Special objects of my invention are the 20 provision of improved means for trunking both ways or in opposite directions over the same trunk-line; the provision of a two-way trunk-line and means for automatically trunking both ways or in opposite directions 25 over the said trunk-line; the provision of means for automatically preventing seizure of a two-way trunk-line during the use thereof for automatically trunking in either direction; the provision of a line-relay 30 adapted to serve as a part of a repeater for repeating switch operating impulses from one section of the line circuit to another, and also as a line-relay for controlling the operation of a trunk-selecting switch mechanism; 35 the provision of a two-way trunk-line having a line-relay adapted for use when the line is used for trunking in either direction; the provision of an automatic telephone selector-switch having line-relays adapted to 40 serve also as a portion of a repeater; the provision of a two-way trunk-line provided at its opposite ends with means for rendering it busy when used for automatically trunking in either direction—that is to say, 45 for establishing a guarding potential at both ends of the trunk-line when the same is used for automatically trunking in either direction; the provision of an improved two-way trunk-line service for use in trunking or extending connections both ways or in opposite directions over one and the same line; and the provision of certain details and features of improvement and combinations tending to increase the general efficiency and service-

ability of a telephone exchange system of 55 this particular character.

To the foregoing and other useful ends, my invention consists in matters hereinafter set forth and claimed.

Figures 1 and 2 together represent diagrammatically the calling subscriber of one central station (Fig. 1) connected with the called substation of a second central station (Fig. 2). Fig. 1 alone shows the calling substation X, the substation telephone line, a first-selector-switch A allotted to said line, and provided with suitable connections to the central battery B. As shown, the said first-selector is represented with the two-way trunking switch C of the calling exchange. Fig. 2 alone represents a called subscriber's station No. 2220, his telephone line and the first-selector A¹ allotted to said line. The two-way trunk switch D of the second central office is shown connected with the connector-switch E, and the latter is shown connected with the called subscriber's line. Said switch D is similar to the switch C of Fig. 1. Fig. 3 is a diagrammatic perspective view of the first-selector A. Fig. 4 is a 80 diagrammatic perspective view of my improved two-way trunk switch D. Fig. 5 is a similar view of the connector-switch E.

As thus illustrated, it will be understood that the subscribers' stations may be of any 85 suitable or approved type. Substation X, as shown, has a ringer 2 normally bridged across the line. Said substation is of the local battery type, in which the primary circuit that comprises the transmitter 3, the 90 battery 4, and primary winding 5 of the induction-coil 6 is retained normally open by the switch-hook 7 at the springs 8 and 9. Said substation is provided with a calling device for operating the switching apparatus at the central office. Said calling device may be of any desired type and is represented as comprising a couple of push-buttons 10 and 11 for operating the springs 12 and 13 with respect to the ground post 14. 100 Said springs 12 and 13, as shown, normally engage the contact-points 15 and 16, respectively, but said connection is broken whenever the said springs are forced onto the ground post 14. Said ground post is normally disconnected from ground, but when the switch-hook is raised a connection to ground is established through the springs

17 and 18. The secondary circuit, of course, comprises the receiver 19 and a secondary winding 20 of the induction-coil 6. Said secondary circuit, when the switch-hook is 5 up, is bridged across the line, and at this time the ringer is cut off. Said switch-hook 7 is provided with a number of cam-arms 21, 22, 23 and 24 for controlling the substation circuits. The cam-arm 22, when the switch-hook is down, engages the ringer circuit spring 25 for closing the ringer circuit, but when the switch-hook rises the said circuit is broken at the said point. There are two other springs 26 and 27 controlled through 10 the medium of the said ringer spring 25. Said springs are normally separated, but when the switch-hook rises the said springs close into contact. The said springs 26 and 27 are included in the secondary circuit for 15 maintaining the said secondary circuit normally open. The primary circuit springs 8 and 9, previously described, are controlled by the cam-arm 23 in such a manner that when the switch-hook is up the said springs 20 are closed and when the switch-hook is down they are open. The cam-arm 24 in turn controls the ground springs 17 and 18 through which the ground post 14 is connected to ground. Lastly, the cam-arm 21 25 operates the release-springs 28, 29 and 30 in such a manner that as the switch-hook descends the said springs are forced together to send simultaneous electric impulses to the central station apparatus over both sides 30 of the subscriber's line. The substation is also provided with a signaling button 31 for operating the spring 32 that normally engages the contact-point 33, against the ground contact 34. By means of said signaling button the connector ringer-relay is 35 operated for signaling a called subscriber in a way that will be described.

The first-selector A is of the well-known and general type described in Patent No. 45 815,321, issued March 13, 1906, to Keith, Erickson and Erickson. Said selector is provided with a switch-shaft 35 for carrying and moving the line-wipers 36 and 37 and the private-wiper 38. Said shaft is operated vertically by the vertical-magnet 39 for raising the said wipers to any desired row or level of the line and private banks 40 and 41, respectively. When raised the shaft is rotated by the rotary-magnet 42. The release-magnet 43 is employed for restoring the switch after it has been operated. The vertical and rotary line-relays 44 and 45, the bridge-cut-off-relay 46, back-release-relay 47, and private-magnet 48 are auxiliaries for controlling said vertical, rotary and release magnets. The switch-shaft has the usual cam 49, the longitudinal teeth 50 for rotating the shaft, and the circular teeth 51 for raising it. Associated with said circular teeth is the channel 52 normally occu-

70 pied by the shaft-rest 53. The switch-shaft is maintained in normal rotary position by the normal post 54 and the normal post-arm 55, against which post the said arm 55 is retained by the spring 56.

The connector E is of the general type described in Patent No. 815,176, issued March 13, 1906, to Keith, Erickson and Erickson. In construction it is very similar to the first-selector, although the circuits are quite 75 dissimilar. Said connector is also provided with a switch-shaft 57 and wipers 58, 59 and 60 to which are allotted the line and private banks 61 and 62, respectively. There is also a shaft-cam 63, the longitudinal 80 teeth 64, circular teeth 65, shaft-rest 66, normal post 67, normal post-arm 68 and the coil-spring 69. Furthermore, there are the vertical magnet 70, the rotary magnet 71, and the release-magnet 72, and in addition 85 the auxiliary vertical and rotary line relays 73 and 74, the vertical and rotary back-bridge-relays 75 and 76, and, the private magnet 77. The connector has a special relay known as the ringer-relay 78 for connecting the ringer generator 79 across the called subscriber's line when a connection is established.

The mechanism of the two-way trunking switch is the same as that of the first-selector, but the circuits are different. There is no bridge-cut-off-relay similar to the bridge-cut-off-relay 46; but the vertical magnet 80, the rotary magnet 81, and the release-magnet 82, together with the private 90 magnet 83, the vertical and rotary line relays 84 and 85, respectively, and the back-release-relay 86 perform very much the same office ascribed to the similar magnets in the first-selector. Whatever difference 95 there is in the operation of said relays and magnets will be set forth. Among the marked features of my improved two-way trunk switch are the vertical and rotary switching relays 87 and 88, respectively. 100 Normally, as in the first-selector, the release-link 89 latches the pin 90 upon the double dog 91, whereby the retracting-spring 92 of the release-armature 93 retains the side switch F in first position, with the escapement-finger 94 behind the lower rearmost escapement-tooth 95, and with the lug 96 of the side switch arm 97 resting against a section 98 of the switch frame. The side switch, of course, is pivotally supported by 105 the points 99; also, the double dog arm 100 engages the link 101 that is pivoted to the side switch at the point 102. It will be evident then that when the stop 96 strikes the switch frame 98 the arm 100 will not be able 110 to carry the side switch any farther, and the double dog 91 will thus reach the limit of its stroke. The adjustment is such that normally—that is, when the side switch is in 115 first position, as shown in Fig. 4—the 120

springs 103 and 104 are retained in engagement, because the release-link 89 cannot be retracted any farther by the retracting-spring 92 after the lug 96 strikes the frame 98; but when the release-link 89 is withdrawn from the lug 90 the retracting-spring 92 carries the link 89 back a little farther, whereby the springs 103 and 104 separate, and the said spring 103 then engages the spring 105. This is a new feature. It will be noticed that the spring 103 is controlled by the link 89 through the medium of the arm 106. The controlling of the spring 103 is not necessarily limited to the method herein shown. Furthermore, it is not necessary that the arm 106 be permanently attached to the link 89. It will be understood that while the double dog 91 is latched by the release-link 89 the release-armature 93 is drawn slightly toward the core of the release-magnet 82; but when the release-link is disengaged, as described, the retracting-spring 92 carries the release-armature 93 back as far as it will go against any suitable stop that may be provided for said armature. As in the first-selector the release-armature retracting-spring 92 (while the double dog is latched by the release-link 89) retains the dogs 107 and 108 away from the shaft; but when the double dog is released by the vertical arm 109 the double dog retracting-spring draws the said dogs toward the shaft in such a manner that the dog 107, by engaging the circular teeth 110, prevents the shaft from falling when raised by the vertical pawl 111 upon the end of the vertical arm 109, as the vertical magnet 80 is energized. When the rotary magnet 81 is energized the rotary-armature 112 is attracted, and among other things that follow the shaft 113 is rotated by the pawl 111 of the rotary arm 115. When the said rotary pawl engages the longitudinal teeth 116 the rotary armature-finger 117 at the same time depresses the private armature 118 and also the interrupter-finger 119 separates the interrupter-springs 120 and 121 to destroy the energizing circuit through the rotary magnet 81, as will be described. The interrupter is represented by the interrupter-finger 119 and the springs 120 and 121. When the shaft is rotated the rotary dog 108 engages the longitudinal teeth 116 and locks the shaft against backward rotation by the tension of the shaft coil-spring 122.

The operation is as follows: When the selector A is operated to connect with the two-way trunk switch C the vertical switching relay 87^c of the said switch C is energized through the private wiper 38 of the calling first-selector when the side switch of the said first-selector passes to third position. The said switching relay then causes the rotary switching relay 88^c to pull up. In the interval between the pulling up of the said

vertical switching relay 87^c and the pulling up of the rotary switching relay 88^c a ground impulse is sent to the vertical trunk-conductor 123 through a circuit that comprises a normally closed switch-point controlled by the said rotary switching relay. Said impulse is comparatively short, for immediately after the vertical switching relay pulls up the established ground circuit is cut off by the rotary switching relay when the said relay opens up the said normally closed switch-point. This preliminary impulse to the said trunk-conductor 123 operates the vertical line-relay 84 of the two-way trunk switch D, so that the vertical magnet 80 is caused to give a slight kick without raising the shaft of the switch D, but sufficient to dislodge the release-link 89 from the double dog 91 and permit the springs 103 and 105 to come into contact after the said spring 103 leaves the spring 104. As a result the trunk-release-conductor 129 that leads to the selector-banks of the second exchange is grounded. Therefore, the seized trunk-line is protected from seizure at both exchanges—at the second exchange, as just described, and at the first exchange when the side switch wiper 130 of the first-selector A engages with the grounded contact 131 thereof.

In detail the switching operations are as follows: When the subscriber at the substation X wishes to call the subscriber at substation #2220 he presses the vertical and rotary buttons 10 and 11 twice and once, twice and once, twice and once, and ten times and once, respectively. When the button 10 is pressed twice for the first time it energizes the vertical line-relay 44 of the first-selector A twice. Said relay in turn energizes the vertical magnet 39 twice and as a result the shaft 35 is raised two steps. The energizing circuit for the vertical line-relay 44 is from ground G to the substation ground G², thence through the ground springs 18 and 17 to the conductors 132 and 133 to the ground post 14, thence to the spring 12, vertical line-conductor 134, side switch wiper 135, contact point 136, conductor 137, vertical line-relay 44, bridge-cut-off-relay springs 138 and 139 to the battery-lead 140, thence through battery B to ground G. The vertical line-relay upon attracting its armature 141 forces the spring 142 onto the ground spring 143. The vertical magnet 39 receives current through the following circuit: from ground G² through the springs 143 and 142 to the conductor 144, private springs 145 and 146 to the vertical magnet 39, thence to the battery-lead 140 and through battery B to ground G. The vertical magnet 39 upon attracting the vertical armature 147 twice through the medium of the vertical arm 148 causes the vertical pawl 149 to engage the circular teeth 51 and to raise the

shaft 35 one step at a time. At the first step of the vertical arm 148 the release-link 150 is drawn by the L-shaped piece 151 from the dog lug 152 of the double dog 153, so that the vertical dog 154 engages the circular teeth 51 to hold the shaft in the first elevated position. The shaft having been raised two steps the line and private wipers are raised to a level opposite the first contact of the second level of their respective banks, and are in readiness to be rotated into engagement with the contacts of said banks. When the subscriber presses the rotary button 11 the rotary line-relay 45 of the first selector is energized in turn and the said relay then causes the private magnet 48 to be magnetized for operating the side switch H. The energizing circuit for the rotary line-relay 45 may be traced from the substation ground G¹ to the ground post 14, thence to the rotary line-conductor 155, side switch wiper 156, contact-point 157, conductor 158, rotary line-relay 45, bridge-cut-off relay springs 159, 138 and 139 to the battery-lead 140 and through battery B to ground G. The rotary line-relay 45 then attracts its armature 160 and thereby presses the spring 161 onto the ground spring 143. The electric current will then flow from ground G² through the springs 143 and 161, conductors 162 and 163 to the private magnet 48, thence to the battery-lead 140 and through battery B to ground G.

Assuming that the first nine contacts of the second level of the private bank 41 are busy, and, therefore, that the first nine trunks of the second level of the line-bank 40 are in use, then when the private magnet 48 by operating its armature causes the side switch H to pass to second position an energizing circuit is established through the rotary magnet 42 that will cause the latter to rotate the shaft one step. At the very first step the private wiper 38 meets a guarding potential at the first contact of the second level of the private bank 41, so that the private magnet 48 is reenergized for locking the side switch in second position until the rotary magnet 42 has carried the wipers past all busy trunk-lines. The private magnet upon becoming energized, as described, attracts the private armature 164, whereby the escapement-tooth 165 clears the escapement-finger 166 and the retracting-spring 167 advances the escapement-finger 166 against the upper rearmost escapement-tooth 168. When the private armature returns to normal position the escapement-finger 166 clears in turn the tooth 168 and the lug 169 at the base of the finger 166 strikes the cam 49 and retains the said escapement-finger 166 between the teeth 165 and 171. Of course, it will be understood that the retracting-spring 167 provides the force that continually advances the side switch from

one position to another during the call. When the side switch passes to second position the side switch wiper 172 engages the grounded contact 173, whereby an energizing circuit for the rotary magnet 42 is established. The current in this circuit passes from ground G³ to the contact-point 173, thence to the side switch wiper 172, conductor 174 to one of the coils of the rotary magnet 42, thence through the springs 175 and 176 and through the other coil of the rotary magnet to the battery-lead 140 and through battery B to ground G. The rotary magnet upon attracting the rotary armature 177 rotates the shaft 35 one step so that the private-wiper 38 engages the first contact of the second level of the private bank 41. The said contact being grounded the private magnet 48 is energized again as follows: from the ground terminal G of battery B through an occupying switch and bank multiplying conductors to the first contact of the second level of the private bank 41, thence to the private wiper 38, conductor 178, back-release-relay 47, conductor 179 to the side switch wiper 180, thence to the contact-point 180, conductors 181 and 183 to the private magnet 48, thence to the battery-lead 140 and through battery B to ground G. The private magnet then attracts its armature 164 and locks the escapement-finger 166 behind the tooth 182. This, of course, occurs before the cam 49 leaves the lug 169. The side switch being thus locked in second position the rotary magnet 42 is energized intermittently as long as the private wiper 38 finds busy contact-points along the second level of the private bank 41. As a result the rotary-armature 177 is attracted step by step until the wipers are carried into engagement with the tenth trunk-line of the second level, which, as stated, is the only trunk-line on said level that is idle.

At the instant that the private wiper 38 leaves the last busy contact the energizing circuit through the private magnet 48 is destroyed and the side switch H passes to third position. The side switch wipers 135 and 156 then engage the contact-points 183 and 184 and the side switch wiper 130 engages the contact-point 181. The side switch wipers 135 and 156 thus extend the subscriber's line-conductors 134 and 155 by way of the conductors 185 and 186 and line wipers 36 and 37, respectively, to the trunk-conductors 187 and 188, as shown in Fig. 1. The engagement between said side switch wiper 130 and contact-point 181, as described, places a guarding potential at the tenth contact of the second level of the private bank 41. The connection between said contact and ground is as follows: from ground G⁴ to the contact-point 181, thence to the side switch wiper 130 and through the back-release-relay 47 to the private wiper 130

38 and to the said contact. The seized trunk-conductors 187 and 188 are thus protected from seizure by other first-selectors which have multiple contacts or terminals 5 of the said seized trunk. At the instant that the said guarding potential is established at the said tenth contact of the second level the vertical switching relay 87° of the two-way trunk switch C is energized. 10 Said relay receives current from the first-selector A, from the ground G⁴ to the private wiper 38, thence to the trunk-release-conductor 189, conductor 190, release-armature springs 124 and 125, conductor 191 to 15 the vertical switching relay 87°, thence to the battery-lead 140 and through battery B to ground G. The said relay upon becoming energized presses the springs 192, 193 and 194 into contact, and as a result two 20 operations are simultaneously accomplished, namely a ground connection is established to the vertical trunk-conductor 123 and an energizing current is sent through the rotary switching relay 88°. The circuit by 25 which the said ground connection is established may be traced from ground G⁵ to the springs 194 and 193, thence through the springs 195 and 196 of the rotary switching relay 88° to the springs 197 and 198 of the 30 vertical switching relay 87° to the conductor 199 and to the vertical trunk-conductor 123. The energizing circuit through the rotary switching relay 88° extends from the same ground G⁵ through the springs 194, 193 and 35 192 to the said relay 88°, thence to the battery-lead 140 and through battery B to ground G. As soon as the said relay becomes energized it attracts its armature and thereby separates the springs 195 and 196 40 so that the ground circuit to the vertical trunk-conductor 123, described, is at once interrupted. The said momentary preliminary ground impulse to the vertical trunk-conductor 123 causes the vertical magnet 80 45 of the two-way trunk switch D at the second exchange to be energized sufficiently to dislodge the release-link 89 from the double dog lug 90, but not so as to cause the shaft 113 of said switch to be raised. The said 50 release-link being dislodged, as described, the armature 92 of the release-magnet 82 is then moved a little farther from the core of the release-magnet 82, and as a result the spring 103 engages the ground 55 spring 195 and places a guarding potential over the trunk-release-conductor 129 at all selector private bank contacts that are multiplied to said trunk-release-conductor. Therefore, the seized trunk is not 60 only protected from seizure at the first central office or station, but at the second central office or station as well. Not only is a short electric impulse sent to the vertical trunk-conductor 123 by the energization of 65 said vertical and rotary switching relays 87° and 88°, as described, but certain circuits are changed around as follows: For instance when the vertical switching relay 87° is energized the vertical line-relay 126 that is normally connected to the vertical 70 trunk-conductor 123 is disconnected from said trunk-conductor and connected instead with the vertical trunk-conductor 187, leading from the first-selector A. The normal connection with the said vertical trunk-conductor 123 is from said relay 126 over the conductor 202 to the contact-point 203, side switch wiper 204, conductor 205, through the vertical switching relay springs 206 and 198 and conductor 199 to the said 75 vertical trunk-conductor 123. The connection between the said vertical line-relay 126 and vertical trunk-conductor 187 is from said vertical line-relay 126 to the conductor 202, contact-point 203, side switch wiper 80 204, and conductor 205 to the spring 206, thence by a new circuit including the spring 207, conductor 208 to the vertical trunk-conductor 187. Furthermore, when the rotary switching relay 88° is energized the 85 rotary line-relay 127 is in a similar manner changed from normal connection through the rotary outgoing trunk-conductor 209 into connection with the local rotary trunk-conductor 188. 90 The normal connection between the rotary line-relay 127 and the outgoing trunk-conductor 209 may be traced from said rotary line-relay 127 to the conductor 210, thence to the contact-point 211, side switch wiper 212, conductor 213 to the rotary switching relay springs 214 and 215, conductor 216 to the outgoing trunk-conductor 209. The 95 temporary circuit between said rotary line-relay 127 and the local rotary trunk-conductor 188 may be traced from the said relay 127, over the same circuit as before, to the spring 214, then to the spring 217, conductor 218, and to the local rotary trunk-conductor 188. The calling subscriber after having 100 pressed the button 10 twice and the button 11 once presses the button 10 twice a second time. Each time that the said button 10 is pressed the vertical line-relay 126, now temporarily connected with the local vertical 105 trunk-conductor 187, is energized. The current for energizing said relay flows from ground G⁵ to the ground post 14, thence through spring 12 to the vertical line-conductor 134, first-selector side switch wiper 135, contact-point 183, conductor 185 to the vertical line-wiper 36, thence to the said vertical local trunk-conductor 187, conductor 120 188, springs 207 and 206, conductor 205, side switch wiper 204, contact-point 203, conductor 202 to the said vertical line-relay 126, thence to the battery-lead 140 and through battery B to ground G. Each time that the 125 said vertical line-relay 126 is energized the springs 219 and 220 are pressed into contact, 130

and, therefore, the vertical line-relay 84 of the switch D is energized also. The energizing circuit for said vertical line-relay 84 extends from ground G⁶ through said springs 220 and 219 and through the vertical switching relay springs 197 and 198 to the vertical trunk-conductor 123. The impulse then travels to the second exchange and passes through the vertical switching relay springs 221 and 222, conductor 223 to the side switch wiper 224, thence to the contact-point 225, conductor 226 to the vertical line-relay 84, thence to battery-lead 140^a and through battery B¹ to ground G¹. The vertical line-relay 126 of the switch C is energized twice, as described, the vertical line-relay 84 of the switch D is also energized twice, and as a result the vertical magnet 80 of the said switch D is also energized twice, raising the shaft of said switch two steps. Said vertical magnet 80 is energized each time that the vertical line-relay 84 presses the springs 227 and 228 into contact. The energizing current for said vertical magnet 80 may be traced from ground G⁷ through the springs 228 and 227 to the vertical switching relay springs 229 and 230, thence to the conductor 231 and private springs 232 and 233 to the vertical magnet 80, thence through battery B¹ to ground G¹. Of course, each time that the said vertical magnet 80 is energized the switch-shaft 113 is raised one step; and since the said magnet is energized twice the switch-shaft raises the wipers 234, 235 and 236 to the second level (as described in connection with the first-selector A) of the line and private banks 237 and 238, respectively. The subscriber having raised the shaft of the switch D to the second level, and placed the line-wipers 234 and 235 and the private wiper 236 in readiness to be rotated into engagement with the line and private banks 237 and 238, then proceeds to press the rotary button 13 once for the second time. As a result the rotary line-relay 127 of the switch C is energized once over the following circuit: from ground G¹ to the ground post 14, thence to the spring 13, rotary line-conductor 155, rotary side switch wiper 156, contact-point 184, conductor 186, rotary line-wiper 37 to the rotary trunk-conductor 188, thence to the conductor 218, rotary switching relay springs 217 and 214 to the conductor 213, side switch wiper 212, contact-point 211 and conductor 210 to the rotary line-relay 127, thence through battery B to ground G. The said rotary line-relay 127 upon attracting its armature presses the spring 239 into engagement with the spring 220 and thereby energizes the rotary line-relay 85, which latter then energizes the private magnet 83. The current for energizing the rotary line-relay 85 of the switch D flows from ground G⁸ through the springs 220 and 239 to the conductor 240, thence through the rotary switching relay springs 241 and 215 to the conductor 216, thence to the rotary trunk-conductor 209, conductor 242 at the switch D, rotary switching relay springs 243 and 244, conductor 245, side switch wiper 246, contact-point 247, conductor 248, rotary line-relay 85 to the battery-lead 140^a and through battery B¹ to ground G¹. The rotary line-relay 85 upon attracting its armature presses the springs 249 and 228 into contact, whereby a flow of current is sent from ground G⁷ through the springs 228 and 249, conductor 250, rotary switching relay springs 251 and 252, conductor 253 to the private magnet 83 (Fig. 4), thence to the battery-lead 140^a and through battery B¹ to ground G¹. When the private magnet 83 is energized it attracts its armature 118 and operates the side switch F in the same manner that the private magnet 48 of the first-selector A operates the side switch H, as described.

Assuming that the first nine trunks leading from the second bank level of the switch D are busy the line-wipers 234 and 235 and the private wiper 236 will be moved, in the manner described in connection with the first-selector A, into engagement with the line bank conductors 254 and 255 and the trunk-release-conductor 256, as shown in Fig. 4. While the private wiper 236 is passing over busy contacts, of course, the private magnet 83 locks the side switch F in second position and establishes an energizing circuit through the rotary magnet 81 until the said rotary magnet rotates the shaft 113, as stated. The energizing circuit is from ground G¹³ to the side switch wiper 256^a, thence through the rotary magnet 81 to battery B¹. When the switch D is thus operated the subscriber's line-conductors 134 and 155 are extended through the first-selector A and through the switches C and D into connection with the connector E, as shown in Figs. 1 and 2. Therefore, when the push-button 10 is pressed twice for the third digit the vertical line-relay 126 of the switch C is energized twice. As a result the vertical line-relay 73 of the connector E is energized twice. The circuit over which the said vertical line-relay 73 is energized has already been pointed out and the circuit over which the vertical trunk-conductor 123 is grounded when the said relay 126 is operated has also been pointed out. Said ground impulse, as stated, begins at ground G⁶ and extends to the vertical trunk-conductor 123, then it extends to the conductor 257, vertical switching relay springs 221 and 222 of the switch D, conductor 223, side switch wiper 224, contact-point 258, conductor 259, vertical line-wiper 234 to the vertical trunk-conductor 254, thence through the vertical line-relay 73 to the battery-lead 140^a and through battery B¹ to ground G¹. When the said ver-

tical line-relay 73 attracts its armature 260 the springs 261 and 262 are pressed into engagement, and as a result the vertical magnet 70 is energized. The current through the 5 said vertical magnet 70 flows from ground G⁸ through the springs 262 and 261, conductor 263, private springs 264 and 265, conductor 266, side switch wiper 267, contact-point 268 to the vertical magnet 70, thence to 10 the battery-lead 140^a and through battery B¹ to ground G¹. The vertical magnet 70 upon attracting its armature 268 twice causes the shaft 57 two steps and places the wipers 58, 59 and 60 opposite the first contact of 15 the second level of their respective banks 61 and 62. The subscriber operates the rotary button 11 again once and thereby energizes the rotary line-relay 127 of the switch C over well-known circuits. The said relay 20 in turn causes the rotary line-relay 74 of the connector E to be energized by a flow of current through a circuit as follows: from ground G⁸ to the rotary trunk-conductor 269, as previously described, thence by the 25 conductor 242 to the rotary switching relay springs 243 and 244, conductor 245, side switch wiper 246, contact-point 269, conductor 270, rotary line-wiper 235, rotary trunk-conductor 255 to the rotary line-relay 74 and 30 to the battery-lead 140^a, thence through battery B¹ to ground G¹. The said rotary line-relay upon energizing presses the spring 271 onto the spring 262 and as a result energizes the private magnet 77. The energizing current through said private magnet 77 flows 35 from ground G⁸ through the springs 262 and 271, conductor 272 to the private magnet 77, thence to battery-lead 140^a and through battery B¹ to ground G¹. The private magnet 77 upon attracting its armature 273 causes the tooth 274 to clear the escape- 40 ment-finger 275, at which time the side switch retracting-spring 276 causes the said finger 275 to engage the tooth 277, and when 45 the armature regains its normal position the said tooth 277 in turn passes the finger 275 and permits the spring 276 to draw the side switch 1 to second position, in which position it is stopped when the lug 278 strikes 50 the cam 63.

Shifting the side switch 1 to second position causes the side switch wiper 267 to leave the contact-point 268 and engage instead the contact-point 279. The result of 55 this change is to withdraw the vertical magnet 70 from the control of the vertical line-relay 73, as described, and to substitute the rotary magnet 71 to the control of said relay instead. The subscriber then proceeds to 60 press the button 10 ten times for the last digit, whereby the vertical line-relay 73 of the connector is energized ten times over circuits that have been pointed out. Said relay upon attracting its armature presses 65 the springs 261 and 262 together. Each time

that the said springs close into contact the rotary magnet 71 is energized once. The current through said rotary magnet flows from ground G⁸ to the side switch wiper 267, as in the previous case. The current 70 then passes to the contact-point 279 and to the rotary magnet 71, thence to battery-lead 140^a and through battery B¹ to ground G¹. Each time that the rotary magnet 71 is energized the shaft 57 is rotated one step by the 75 rotary armature 280, in the well-known manner; and since the subscriber presses the said vertical button ten times the shaft 57 is rotated ten steps and the line-wipers 58 and 59 are brought into connection with 80 the trunk-line-conductors 281 and 282 leading from the tenth terminal of the second level of the line-bank 61, and the private wiper 60 into connection with the private normal conductor 283 leading from the 85 tenth contact of the second level of the private bank 62. When the subscriber presses the rotary button 11 for the last time he again energizes the rotary line-relay 127 of the switch C, which in turn energizes the 90 rotary line-relay 74 of the connector E, as before. The rotary line-relay 74 in turn energizes the private magnet 77 over circuits that are known, whereby it operates its armature 273 to permit the side switch 1 95 to pass to third position in a way that is well known. When the said side switch passes to third position the subscriber's extended line-conductors 254 and 255 are placed in connection with the normal conductors 281 and 282 as soon as the side switch wipers 284 and 285 engage the contact-points 286 and 287. The connection between the conductor 254 and the normal conductor 281 is established through the 100 condenser 288, conductor 289, ringer relay springs 290 and 291, side switch wiper 284, contact-point 286, conductor 292, vertical line-wiper 58 to the vertical normal conductor 281. The extended rotary line-conductor 255 connects with the rotary normal conductor 282 through the condenser 293, conductor 294, ringer relay springs 295 and 296, side switch wiper 285, contact-point 105 287, conductor 297, rotary line-wiper 59 to the said rotary normal conductor 282. When the side switch passes to third position not only are the called subscriber's conductors extended, as described, but also a 110 guarding potential is placed at the tenth contact of the second level of the private bank 62 to protect the seized line. This guarding potential is established from the ground G⁸ to the contact-point 227, side switch wiper 302 to the private wiper 60 and 115 thence to the said contact. Said guarding potential, furthermore, energizes the bridge-cut-off-relay 225 of the selector A¹, whereby the vertical and rotary line-relays 200 and 201 are removed from across the normal 120

conductors 281 and 282, for reasons that are obvious. The energizing current in said relay 225 flows from ground G^1 to the private wiper 60, conductor 283, through the normal springs and winding of the bridge-cut-off relay 225, thence to battery-lead 140^a and through battery B^1 to ground G^1 . Since the normal conductors 281 and 282 lead directly to the substation #2220, the 10 calling subscriber is then in readiness to signal the subscriber at the called substation. If said subscriber should be busy, however, for any reason whatever—that is, either by reason of being called or by calling—the tenth contact of the second level of the private bank 62 would be connected to ground in the well-known way. In such a case the connection would not be completed between the conductors 254 and 281 15 and the conductors 255 and 282, and the connector instead would be released when the calling subscriber presses the rotary button 11 for the last time.

The operation is as follows: The side 25 switch I being in second position, and the private wiper 60 having engaged the tenth contact of the second level of the private bank 62, and if the said contact is grounded as stated, then when the button 11 is pressed 30 the calling subscriber instead of securing connection with the desired line merely energizes the release magnet 72 of the connector E. When the said button is pressed, as stated, the rotary line-relay 74 is energized, as previously described, and the private magnet 77 is also energized as a result. Said private magnet attracts its armature 273 and causes the lateral arm 298 to press the private springs 299 and 300 in contact 35 and to separate the springs 265 and 264. When the said springs 299 and 300 engage a current then flows from ground to the said private contact in question, by way of the first-selector of the desired subscriber (if 40 said subscriber is calling), or by way of some other connector if the desired subscriber has been called. From the said contact the current then passes to the private wiper 60, conductor 301, side switch wiper 50 45 302, contact-point 303, conductor 304, private springs 299 and 300, conductors 305 and 306 to the release-magnet 72, thence to the battery-lead 140^a and through battery B^1 to ground G^1 . The release-magnet 72 then 55 attracts its armature 307 and thereby restores the double dog 308. As a result the side switch I is restored to normal position and the switch-shaft 57 is permitted to return to normal position. The calling subscriber, thinking he has established connection, presses the signal button 31 and thereby grounds the vertical line-conductor 134 over the following path: The circuit is from ground G^1 and through the springs 18 and 60 65 17 to the contact-point 31, thence through

the spring 32, springs 26 and 27, contact-point 15 and spring 12 to the vertical line-conductor 134. The result is that the vertical line-relay of the switch C is energized, the vertical trunk-conductor 123 is grounded 70 and the vertical line-relay 73 of the connector E is energized. Said relay, as before, presses the springs 261 and 262 together, and since the side switch I is now in first position the vertical magnet 70 is energized, 75 as has been described. Said vertical magnet then raises the shaft 57 and permits the switch-shaft springs 309 and 310 to come into contact and busy signaling current is sent to the subscriber's station, notifying the 80 subscriber that the called line is busy. The busy signal current is generated in the coil 311, shown in Fig. 2, and it then flows by the conductor 312 to the switch-shaft spring 309, thence through the mate spring 310 to the 85 side switch contact-point 313, side switch wiper 285, ringer relay springs 296 and 295, conductor 294, condenser 293, conductor 255, wiper 235 of the switch D, conductor 270, contact-point 269, side switch wiper 246, conductor 245, rotary switching relay springs 244 and 243, conductor 242, rotary trunk-conductor 209, condenser 314 of the switch C, conductor 187, line-wiper 36 of the first-selector A, conductor 185, contact-point 90 183, side switch wiper 135, vertical line-conductor 134, spring 12, contact-point 15, springs 27 and 26, signaling button springs 32 and 33, secondary winding 20 of the induction-coil 6, receiver 19 to the contact-point 100 16, spring 13, rotary line-conductor 155, side switch wiper 156, and contact-point 184, conductor 186, rotary line-wiper 37, rotary trunk-conductor 188, condenser 315, vertical trunk-conductor 123, vertical switching relay springs 221 and 222 of the switch D, conductor 323, side switch wiper 224, contact-point 258, conductor 259, vertical line-wiper 234, vertical trunk-conductor 254, vertical line-relay 73 to the battery-lead 140^a, 110 and back again to the coil 311. The subscriber upon hearing the busy signal will restore his receiver and thereby release all the central office apparatus. When the switch-hook descends the vertical and rotary line-conductors 134 and 155 are grounded simultaneously. The connection between ground and said conductors is from ground G^1 through the springs 18 and 17 to the conductor 132, thence through the release-springs 30 and 29 to the rotary line-conductor 155, and through the release-springs 30, 29 and 28 to the vertical line-conductor 134. Grounding said vertical and rotary line-conductors simultaneously energizes the 120 125 vertical and rotary line-relays 126 and 127 of the switch C simultaneously, and said relays in turn cause the vertical and rotary trunk-conductors 123 and 209 to be grounded simultaneously, and as a result the vertical 130

and rotary line-relays 73 and 74 of the connector E are also energized simultaneously. The circuits for energizing all of said relays are well-known, since they have already been 5 traced.

- When the connector line-relays 73 and 74 pull up, as stated, the trunk release springs 316 and 317 are pressed into contact. As a result an energizing circuit is completed 10 through the release-magnet 72 of the connector E in series with the back-release-relay 86 of the switch D. The current flows from ground G¹⁰ at the trunk switch D to the side switch contact-point 318, side switch wiper 319, conductor 320, back-release-relay 86, conductor 321, private wiper 236, trunk release conductor 256, trunk release springs 316 and 317, conductor 306 to the release-magnet 72, thence to the battery-lead 140° 15 and through battery B¹ to ground G¹. When the release-magnet 72 attracts its armature 307 the connector-switch is released, as before, but the relays 73 and 74 and the release-magnet 72 are not deenergized at 20 once. The back-release relay 86 of the trunk switch D being energized at the same time that the release-magnet 72 is energized presses the springs 322 and 323 into contact, thereby energizing the release-magnet 82 of the said switch D. The current through 25 said release-magnet 82 flows from ground G¹¹ and through the springs 322 and 323 to the said release-magnet, thence to the battery-lead 140° and through battery B¹ to ground G¹. When the said release-magnet 82 attracts its armature 93 the release-link 89 is thrust over the lug 90 and at the same 30 time the spring 103 controlled by said release-link withdraws from the spring 105 35 and engages the spring 104. The said release-magnet stays energized as long as the subscriber's release-springs remain in contact, and the switch is not released until the said release-springs disengage. When the 40 line-relays 126 and 127 of the trunk switch C are energized simultaneously the trunk release springs 324 and 325 are pressed into contact, thereby placing the release-magnet 326 in series with the back-release-relay 47 45 of the first-selector A. When the back-release-relay 47 energizes it closes the back-release-relay springs 327 and 328 into contact, establishing an energizing circuit through the release magnet 43. The current 50 run in said circuit flows through ground G¹², through the springs 327 and 328 to the release-magnet 43, thence to the battery-lead 140 and through battery B to ground G. The release-magnet 43 of the first-selector A 55 remains energized after latching the double dog 153 in the same manner stated in connection with the trunk switches C and D and does not release the switch until the release-springs at the substation disengage. 60 At the instant that the said release-springs 65

disengage (when the switch-hook has descended sufficiently) the ground circuit to the line-conductors 134 and 155 is interrupted and as a result the line-relays 126 and 127 of the trunk switch C deenergize. The 70 ground connection to the trunk conductors 123 and 209 is removed in turn so that the vertical and rotary line-relays 73 and 74 of the connector-switch also deenergize. The 75 said connector line-relays upon deenergizing destroy the circuit in which the back-release-relay 86 of the trunk switch D and the release-magnet 72 of the connector E are included. Said relay and magnet, of course, will then at once deenergize. The release-magnet 72 will restore the release-armature to normal position, but the back-release-relay 86 (when it permits the springs 322 and 323 to separate) deenergizes the release-magnet 82, at which time the release-armature 93 is retracted by the retracting-spring 92, whereby the double dog 91 is withdrawn into normal position. However, the release-armature 93 does not return far enough to separate the springs 103 and 104. 90 When the said double dog is restored, as stated, the side switch F and the switch-shaft 113 are restored. Not only do the line-relays 126 and 127 of the trunk switch C remove the ground connections to the trunk-conductors 123 and 209, as stated, but at the 95 same time, when the springs 324 and 325 separate, the circuit that comprises the release magnet 326 and the back-release-relay 47 of the first-selector A is broken, whereby 100 said magnet and relay are deenergized. When the back-release-relay 47 permits the springs 327 and 328 to separate the release-magnet 43 is deenergized, so that the side switch H and switch-shaft 35 return to normal position. 105 As soon as the private wiper 38 of the first-selector A leaves the engaging contact the energizing circuit that has been maintained all along through the vertical switching relay 87 is broken so that said relay is 110 deenergized and restores the springs under its control to normal position. Of course, as soon as the springs 192, 193 and 194 separate the energizing circuit through the rotary switching relay 88 is in turn broken, 115 whereby the said relay may restore the springs it controls to normal position. But if the subscriber is not busy and the connection is established, as originally described, then when the subscriber presses his signalling button 31 and grounds the vertical line-conductor 134 he energizes the vertical line-relay 73 of the connector, as in the last case; but instead of raising the switch-shaft 57 the 120 ringer relay 78 is energized, since the side-switch I is in third position, and since the side switch wiper 267 is in engagement with the contact-point 329. The current for energizing said relay flows from ground G⁸ to the side switch wiper 267, thence through 125 130

the contact-point 329 to the ringer relay 78 and to the battery-lead 140^c and through battery B¹ to ground G¹.

When the ringer relay attracts its armature it forces the springs 296 and 291 onto the springs 330 and 331 and thereby connects the ringer generator 79 across the normal conductors 281 and 282 that lead to the called subscriber's station. Ringing current then flows from the ringer generator 79 to the ringer relay springs 331 and 291, thence to the side switch wiper 284, contact-point 286, conductor 292, vertical line-wiper 58, vertical normal conductor 281, vertical line-conductor 332 to the switch-hook 333, can-arm 334, ringer spring 335, ringer 336, rotary line-conductor 337, rotary normal conductor 282, rotary line-wiper 59, conductor 297, contact-point 287, side switch wiper 285, ringer relay springs 296 and 330 to the ringer generator 79. The subscriber at the substation #2220 answers by removing his receiver 338 from the switch-hook 333, and when the switch-hook permits the springs 369 and 349 to come into contact the talking sets of the two subscribers are placed across the common connecting line so that they may talk to each other. The voice-currents will pass from the secondary winding 20 of the subscriber X to the receiver 19, thence to the rotary line-conductor 155, side switch wiper 156 of the first-selector A, contact-point 184, conductor 188, condenser 315, vertical trunk-conductor 123, vertical switching relay springs 221 and 222, conductor 223, side switch wiper 224, contact-point 258, and vertical line-wiper 234, conductor 254, condenser 288, ringer relay springs 290 and 291, side switch wiper 284, contact-point 286, conductor 292, vertical line-wiper 58, vertical normal conductor 281, vertical line-conductor 332, springs 340 and 339, secondary winding 341 of the induction-coil 342, receiver 338, rotary line-conductor 337, rotary normal conductor 282, rotary line-wiper 59, conductor 297, contact-point 287, side switch wiper 285, ringer relay springs 296 and 295, conductor 294, condenser 293, rotary trunk-conductor 255, rotary line-wiper 235, conductor 270, contact-point 269, side switch wiper 246, conductor 245, rotary switching relay springs 244 and 243, rotary trunk-conductor 209, condenser 314, vertical trunk-conductor 187, vertical line-wiper 36, conductor 185, contact-point 183, side switch wiper 135, vertical line-conductor 134, spring 12, contact-point 15, springs 27 and 26 and back to the secondary winding 20 of the induction-coil 6. Over the said circuit the 60 subscribers, of course, may converse with each other indefinitely. When the subscribers are through talking, and if the calling subscriber restores his receiver and thereby grounds the vertical and rotary line-conductors, as in the previous case, the switches are

then released in the same manner. The only difference is that the connector is in this instance in third position, so that when the release-magnet 72 of the said connector is energized and the double dog 308 restored 70 the switch-shaft rotates first to normal rotary position before it can fall to normal vertical position. Also, as soon as the private wiper 60 leaves the engaging contact the energizing circuit through the bridge-cut-off-relay 225 of the first-selector A¹ is destroyed, whereby the said relay restores the vertical and rotary line-relays 200 and 201 across the subscriber's line. It should be evident that if a call were to come from 80 the second exchange for the first exchange the trunk switch D would take the place of the trunk switch C, and vice versa. It will be understood, of course, that since the vertical switching relay 87^c of the switch C is 85 identical to the vertical switching relay 87 of the switch D, that the springs 343, 197, 198, 206, 207, 192, 193 and 194 have their counterparts in the springs 230, 229, 221, 222, 344, 345, 346 and 347; and that since the 90 rotary switching relay 88^c of the switch C is identical with the rotary switching relay 88 of the switch D, the springs 195, 196, 217, 214, 215, 241 and 348 have their counterparts in the springs 349, 350, 351, 244, 243, 251 and 95 252, and also that the springs 124 and 125 are similar to the springs 193 and 104, respectively.

In order to regulate the length of the preliminary ground impulse that is sent over 100 the vertical trunk-conductor 123 for dislodging the release-link of the trunk switch at the ether end, any means well-known to the telephone art may be resorted to. If it is found that the relay 88^c, for instance, acts 105 a little too quickly it may be encircled with a copper shield to make it work somewhat slowly. The length of the contact may be controlled also to a great extent by a proper adjustment of the springs. The resistance 110 of the switching relays 87 and 88 may be varied, but good results are obtained when they are wound to thirteen hundred ohms; the line-relays 84 and 85 to five hundred ohms each; the back-release-relay 86 to one-half ohm; the private magnet 83 to three hundred and fifty ohms; the vertical magnet 89, rotary magnet 81 and release-magnet 82 to sixty ohms each.

Thus it will be seen that I provide a two-way trunk-line service for use in trunking or extending connections both ways or in opposite directions over one and the same trunk-line. In this way a trunk-line of this character can be used in opposite directions—that is to say, it can be used by one subscriber for extending a connection from his line to the called subscriber's line, and it can also be used for trunking or extending connections in an opposite direction. 130

Regardless of which way the automatic trunking is progressing over the two-way trunk-line, it is invariably the case that a guarding potential is established at both 5 ends of the said line, whereby the line is protected against seizure by other subscribers. With this arrangement a subscriber can use the trunk-line for trunking and calling in one direction, and when he does so no subscriber 10 can seize the same line at its other end and attempt to use it in an opposite direction. It will be understood, of course, that when a subscriber seizes one end of a two-way trunk-line no other subscriber can 15 then seize or establish connection with the same end of such line. The two selectors or trunk-selecting switch mechanisms located at opposite ends of the two-way trunk-line are each provided with line-relays 20 adapted to serve also as a portion of the repeating apparatus by which switch operating impulses are repeated from one to another of the inductively connected sections of the line circuit. With this arrangement 25 the vertical line-relay of the combined selector and repeater C is adapted to repeat switch operating impulses into either a local or a line circuit, according to which way the automatic trunking is progressing 30 over the two-way trunk. If the calling is progressing in one direction over the two-way trunk-line the said vertical line-relay will then repeat the switch operating impulses from the vertical side of the trunk-line to the local circuit including the associated vertical magnet; but if the calling 35 is progressing in the opposite direction, then the said vertical line-relay will repeat switch operating impulses from the vertical side 40 of the subscriber's line to the vertical side of the two-way trunk-line. With such arrangement it is not necessary to employ one or more trunk-lines for trunking and calling in one direction, and one or more trunk-lines 45 for trunking and calling in the opposite direction. With my improved arrangement trunking can be carried on between two automatic exchanges in opposite directions over one and the same trunk-line. For the 50 broader purposes of my invention I, therefore, do not limit myself to the exact construction shown and described.

It will be seen that the two-way trunk-line is provided with means for automatically extending connection therefrom, in either direction, and that additional automatic switching means are provided for extending connection to either end of the trunk-line. With this arrangement each 55 end of the two-way trunk-line is provided with a set of wipers or line terminals for extending connection therefrom, and each end of the trunk-line is also provided with a set of multiple terminals or bank contacts 60 by which a connection is extended thereto.

It will be understood, of course, that the subscribers' lines are each provided with a set of wipers or other suitable individual line terminals for extending connection therefrom, and with a set of multiple bank 70 contacts or terminals for extending connection thereto. In this way any subscriber can call any other subscriber's telephone line, and if the calling and called telephone lines are located at different exchanges, the connection will then be established over a trunk-line between the same. Subsequently the same trunk-line can then be employed for calling and extending connections in the opposite direction. 75

In a telephone system of the foregoing character it will be seen that the two-way trunks are each composed of parallel metallic conductors, and each trunk is necessarily and invariably used in its entirety— 80 that is to say, its conductors cannot be used separately in the establishment of any talking circuit or connection. Furthermore, the battery, it will be seen, is normally free from closed circuits in view of the fact that 85 none of the switches have normally closed energizing circuits, and consequently said switches are all normally demagnetized. It will also be seen that the ringing of a called subscriber is directly under the control of 90 the calling subscriber, inasmuch as the calling subscriber must press the ringing key at the calling substation in order to bring about the signaling of the called subscriber. Again, the two-way trunk has an individual 95 switch therefor at each end, and each switch is adapted only for extending connection from the end of the trunk, and its movable line wipers are operated for no other purpose—that is, can not be operated to extend 100 connection from the end of any other trunk. 105

What I claim as my invention is:—

1. In a telephone exchange system, the combination of a two-way trunk-line, automatic switching means for trunking in one 110 direction over the entire length of said line, and automatic switching means for trunking in the opposite direction over the said line by automatically establishing connection with the other end thereof, said switching 115 means including a switch which is normally deenergized.

2. In a telephone exchange system, the combination of a two-way trunk-line, subscribers' telephone lines, automatic switching means for seizing and thereby extending connection over said trunk-line to a called telephone line in one direction, and automatic switching means for seizing and thereby extending connection over said trunk-line 120 to another called telephone line in the opposite direction, said switching means including a switch which is normally deenergized. 125

3. In a telephone exchange system, the combination of a two-way trunk-line, a nor- 130

- normally deenergized trunk-selector for automatically trunking over said line in one direction, and another automatic trunk-selector for automatically trunking over said line in the opposite direction.
4. In a telephone exchange system, the combination of a two-way trunk-line, a repeater for use in trunking over said line in one direction, another repeater for trunking over said line in the opposite direction, automatic switches, and means for causing said repeaters to transmit switch operating impulses over said line.
5. In a telephone exchange system, the combination of a two-way trunk-line, a line-relay at each end of said line, normally deenergized automatic switches controlled by said relays, means for supplying switch operating impulses over said line in one direction, to energize one of said relays, and means for supplying switch operating impulses over said line in the opposite direction, to energize the other relay.
6. In a telephone exchange system, the combination of a two-way trunk-line, line-relays at opposite ends of said trunk-line, automatic switches controlled by said line-relays, means for using the relays at both ends of the trunk-line when the automatic switch is operated at one end thereof, and means for using the relays at both ends of the trunk-line when the automatic switch is operated at the other end thereof.
7. In a telephone exchange system, the combination of a two-way trunk-line, a line-relay at each end of said trunk-line, an automatic switch controlled by one relay, another automatic switch controlled by the other relay, means for causing one relay to control the other relay when the trunk-line is used for trunking in one direction, and means for causing the other relay to control the said one relay when the trunk-line is used for trunking in the opposite direction.
8. In a telephone exchange system, the combination of a two-way trunk-line, a pair of line-relays normally bridged across one end of said trunk-line, a pair of line-relays normally bridged across the other end of said trunk-line, an automatic switch controlled by one pair of relays, an automatic switch controlled by the other pair of relays, each automatic switch being provided with means by which it may establish connection from the trunk-line, and each end of said trunk-line being provided with means for establishing connection thereto.
9. In a telephone exchange system, the combination of a two-way trunk-line, normally deenergized automatic switches for extending connection from either end of said trunk-line, and automatic trunk-selecting switches for extending connection to either end of said trunk-line.
10. In a telephone exchange system, the combination of a two-way trunk-line, a set of multiple terminals connected with one end of said trunk-line, a set of multiple terminals connected with the other end of said trunk-line, normally deenergized automatic trunk-selecting switches for extending connection to either end of the said trunk-line through the said multiple terminals, and means for extending connection from either end of said trunk-line.
11. In a telephone exchange system, the combination of a two-way trunk-line, normally deenergized automatic switches for extending connection from either end of said trunk-line, and suitable means for extending connection to either end of said trunk-line, said automatic switches common to the subscribers and individual to said trunk-line.
12. In a telephone exchange system, the combination of a two-way trunk-line, normally deenergized automatic switching machinery for extending connection from either end of said trunk-line, said switching machinery common to the subscribers, and automatic switching machinery for extending connection to either end of said trunk-line.
13. In a telephone exchange system, the combination of a two-way trunk-line, automatic trunk-selecting switch mechanisms for extending connection to either end of said trunk-line, said mechanisms controllable in accordance with a digit of the called number, and automatic switch mechanisms common to the subscribers and allotted to said trunk-line, for extending connection from either end thereof.
14. In a telephone exchange system, the combination of a two-way trunk-line, a pair of relays individual to one end of said line, a pair of relays individual to the other end of said line, and automatic means common to the subscribers and controlled by said relays for trunking in opposite directions over said line.
15. In a telephone exchange system, the combination of a two-way trunk-line, automatic switches, and repeaters for transmitting switch operating impulses over said line in either direction.
16. In a telephone exchange system, the combination of a two-way trunk-line, automatic trunk-selecting means for trunking in one direction over said line, automatic trunk-selecting means for trunking in the opposite direction over the said line, and automatic means for establishing a guarding potential for both ends of said trunk-line when the same is used for trunking in either direction.
17. In a telephone exchange system, the combination of a two-way trunk-line, subscribers' telephone lines, automatic means for extending connection over said trunk-

line to a called telephone line in one direction, automatic means for extending connection over said trunk-line to another called telephone line in the opposite direction, and 5 automatic means for establishing a guarding potential for both ends of said trunk-line when the same is used for trunking in either direction.

18. In a telephone exchange system, the 10 combination of a two-way trunk-line, a selector for automatically trunking over said line in one direction, another selector for automatically trunking over said line in the opposite direction, and automatic means for 15 establishing a guarding potential for both ends of said trunk-line when the same is used for trunking in either direction.

19. In a telephone exchange system, the 20 combination of a two-way trunk-line, a repeater for use in trunking over said line in one direction, another repeater for trunking over said line in the opposite direction, automatic switches, means for causing said repeaters to transmit switch operating impulses over said line, and automatic means for establishing a guarding potential for both ends of said trunk-line when the same is used for trunking in either direction.

20. In a telephone exchange system, the 30 combination of a two-way trunk-line, a line-relay at each end of said line, automatic switches controlled by said relay, means for transmitting switch operating impulses over said line in one direction, means for transmitting switch operating impulses over said line in the opposite direction, and automatic means for establishing a guarding potential for both ends of said trunk-line when the same is used for trunking in either direction.

21. In a telephone exchange system, the 40 combination of a two-way trunk-line, line-relays at opposite ends of said trunk-line, automatic switches controlled by said line-relays, means for using the relays at both ends of the trunk-line when the automatic switch is operated at one end thereof, means for using the relays at both ends of the trunk-line when the automatic switch is operated at the other end thereof, and automatic 45 means for establishing a guarding potential for both ends of said trunk-line when the same is used for trunking in either direction.

22. In a telephone exchange system, the 50 combination of a two-way trunk-line, a line-relay at each end of said trunk-line, an automatic switch controlled by one relay, another automatic switch controlled by the other relay, means for causing one relay to control the other relay when the trunk-line is used 55 for trunking in one direction, means for causing the other relay to control the said one relay when the trunk-line is used for trunking in the opposite direction, and automatic means for establishing a guarding po-

tential for both ends of said trunk-line when 65 the same is used for trunking in either direction.

23. In a telephone exchange system, the 70 combination of a two-way trunk-line, a pair of line-relays normally bridged across one end of said trunk-line, a pair of line-relays normally bridged across the other end of said trunk-line, an automatic switch controlled by one pair of relays, an automatic switch controlled by the other pair of relays, each automatic switch being provided with means by which it may establish connection from the trunk-line, each end of 75 said trunk-line being provided with means for establishing connection thereto, and automatic means for establishing a guarding potential for both ends of said trunk-line when the same is used for trunking in either direction.

24. In a telephone exchange system, the 80 combination of a two-way trunk-line, automatic switches for extending connection from either end of said trunk-line, automatic switches for extending connection to either end of said trunk-line, and automatic means for establishing a guarding potential for both ends of said trunk-line when the same is used for trunking in either direction.

25. In a telephone exchange system, the 85 combination of a two-way trunk-line, a set 90 of multiple terminals connected with one end of said trunk-line, a set of multiple terminals connected with the other end of said trunk-line, automatic switches for extending connection to the said trunk-line 95 through the said multiple terminals, means for extending connection from either end of said trunk-line, and automatic means for establishing a guarding potential for both ends of said trunk-line when the same is used for trunking in either direction.

26. In a telephone exchange system, the 100 combination of a two-way trunk-line, automatic switches for extending connection from either end of said trunk-line, suitable 105 means for extending connection to either end of said trunk line, and automatic means for establishing a guarding potential for both ends of said trunk-line when the same is used for trunking in either direction.

27. In a telephone exchange system, the 110 combination of a two-way trunk-line, automatic switching machinery for extending connection from either end of said trunk-line, automatic switching machinery for extending connection to either end of said trunk-line, and automatic means for establishing a guarding potential for both ends of said trunk-line when the same is used for trunking in either direction.

28. In a telephone exchange system, the 115 combination of a two-way trunk-line, automatic trunk-selecting switch mechanisms for 120

extending connection to either end of said trunk-line, automatic trunk-selecting switch mechanisms for extending connection from either end of said trunk-line, and automatic means for establishing a guarding potential for both ends of said trunk-line when the same is used for trunking in either direction.

29. In a telephone exchange system, the combination of a two-way trunk-line, a pair of relays individual to one end of said line, a pair of relays individual to the other end of said line, automatic means controlled by said relays for trunking in opposite directions over said line, and automatic means for establishing a guarding potential for both ends of said trunk-line when the same is used for trunking in either direction.

30. In a telephone exchange system, the combination of a two-way trunk-line, automatic switches, repeaters for transmitting switch operating impulses over said line in either direction, and automatic means for establishing a guarding potential for both ends of said trunk-line when the same is used for trunking in either direction.

31. In a telephone exchange system, the combination of a two-way trunk-line, normally deenergized automatic switching means for trunking in one direction over said line, automatic switching means for trunking in the opposite direction over the said line, and automatic means for preventing seizure of either end of said trunk-line when the same is used for trunking in either direction.

32. In a telephone exchange system, the combination of a two-way trunk-line, subscribers' telephone lines, normally deenergized automatic switching means for extending connection over said trunk-line to a called telephone line in one direction, automatic switching means for extending connection over said trunk-line to another called telephone line in the opposite direction, and automatic means for preventing seizure of either end of said trunk-line when the same is used for trunking in either direction.

33. In a telephone exchange system, the combination of a two-way trunk-line, a normally deenergized automatic trunk selector for automatically trunking over said line in one direction, another automatic trunk selector for automatically trunking over said line in the opposite direction, and automatic means for preventing seizure of either end of said trunk-line when the same is used for trunking in either direction.

34. In a telephone exchange system, the combination of a two-way trunk-line, a repeater for use in trunking over said line in one direction, another repeater for trunking over said line in the opposite direction, automatic switches, means for causing said re-

peaters to transmit switch operating impulses over said line, and automatic means for preventing seizure of either end of said trunk-line when the same is used for trunking in either direction.

35. In a telephone exchange system, the combination of a two-way trunk-line, a line-relay at each end of said line, normally deenergized automatic switches controlled by said relays, means for supplying switch operating impulses over said line in one direction to energize one of said relays, means for supplying switch operating impulses over said line in the opposite direction, to energize the other relay, and automatic means for preventing seizure of either end of said trunk-line when the same is used for trunking in either direction.

36. In a telephone exchange system, the combination of a two-way trunk-line, line-relays at opposite ends of said trunk-line, automatic switches controlled by said line-relays, means for using the relays at both ends of the trunk-line when the automatic switch is operated at one end thereof, means for using the relays at both ends of the trunk-line when the automatic switch is operated at the other end thereof, and automatic means for preventing seizure of either end of said trunk-line when the same is used for trunking in either direction.

37. In a telephone exchange system, the combination of a two-way trunk-line, a line-relay at each end of said trunk-line, an automatic switch controlled by one relay, another automatic switch controlled by the other relay, means for causing one relay to control the other relay when the trunk-line is used for trunking in one direction, means for causing the other relay to control the said one relay when the trunk-line is used for trunking in the opposite direction, and automatic means for preventing seizure of either end of said trunk-line when the same is used for trunking in either direction.

38. In a telephone exchange system, the combination of a two-way trunk-line, a pair of line-relays normally bridged across one end of said trunk-line, a pair of line-relays normally bridged across the other end of said trunk-line, an automatic switch controlled by one pair of relays, an automatic switch controlled by the other pair of relays, each automatic switch being provided with means by which it may establish connection from the trunk-line, each end of said trunk-line being provided with means for establishing connection thereto, and automatic means for preventing seizure of either end of said trunk-line when the same is used for trunking in either direction.

39. In a telephone exchange system, the combination of a two-way trunk-line, normally deenergized automatic switches for

- extending connection from either end of said trunk-line, automatic trunk-selecting switches for extending connection to either end of said trunk-line, and automatic means 65 for preventing seizure of either end of said trunk-line when the same is used for trunking in either direction.
40. In a telephone exchange system, the combination of a two-way trunk-line, a set 10 of multiple terminals connected with one end of said trunk-line, a set of multiple terminals connected with the other end of said trunk-line, normally deenergized automatic trunk-selecting switches for extending connection to either end of the said trunk-line through the said multiple terminals, means 15 for extending connection from either end of said trunk-line, and automatic means for preventing seizure of either end of said trunk-line when the same is used for trunking in either direction.
41. In a telephone exchange system, the combination of a two-way trunk-line, normally deenergized automatic switches for 20 extending connection from either end of said trunk-line, suitable means for extending connection to either end of said trunk-line, said automatic switches common to the subscribers and individual to said trunk-line, and automatic means for preventing seizure of either end of said trunk-line when the same is used for trunking in either direction.
42. In a telephone exchange system, the combination of a two-way trunk-line, normally deenergized automatic switching machinery for extending connection from either end of said trunk-line, said switching machinery common to the subscribers, automatic switching machinery for extending connection to either end of said trunk-line, and automatic means for preventing seizure of either end of said trunk-line when the same is used for trunking in either direction.
43. In a telephone exchange system, the combination of a two-way trunk-line, automatic trunk-selecting switch mechanisms for extending connection to either end of said trunk-line, said mechanisms controllable in accordance with a digit of the called number, automatic switch mechanisms common to the subscribers for extending connection from either end of said trunk-line, and automatic means for preventing seizure of either end of said trunk-line when the same is used for trunking in either direction.
44. In a telephone exchange system, the combination of a two-way trunk-line, a pair 60 of relays individual to one end of said line, a pair of relays individual to the other end of said line, automatic means common to the subscribers and controlled by said relays for trunking in opposite directions over said line, and automatic means for preventing 65 seizure of either end of said trunk-line when the same is used for trunking in either direction.
45. In a telephone exchange system, the combination of a two-way trunk-line, automatic switches, repeaters for transmitting switch operating impulses over said line in either direction, and automatic means for preventing seizure of either end of said trunk-line when the same is used for trunking in either direction.
46. In a telephone exchange system, the combination of a two-way trunk-line, normally deenergized automatic switching means for trunking in one direction over 70 said line, automatic switching means for trunking in the opposite direction over the said line, another trunk conductor, and a local trunk release circuit at each end of said trunk-line, which circuit includes said 75 last-mentioned trunk conductor.
47. In a telephone exchange system, the combination of a two-way trunk-line, subscribers' telephone lines, automatic switching means for extending connection over 80 said trunk-line to a called telephone line in one direction, automatic switching means for extending connection over said trunk-line to another called telephone line in the opposite direction, another trunk conductor 85 and a local trunk release circuit at each end of said trunk-line, which circuit includes said last-mentioned trunk conductor.
48. In a telephone exchange system, the combination of a two-way trunk-line, an 90 automatic trunk-selector for automatically trunking over said line in one direction, another automatic trunk-selector for automatically trunking over said line in the opposite direction, another trunk conductor and a 95 local trunk release circuit at each end of said trunk-line, which circuit includes said last-mentioned trunk conductor.
49. In a telephone exchange system, the combination of a two-way trunk-line, a repeater for use in trunking over said line in one direction, another repeater for trunking over said line in the opposite direction, automatic switches, means for causing said repeaters to transmit switch operating impulses over said line, and a local trunk release circuit at each end of said trunk-line.
50. In a telephone exchange system, the combination of a two-way trunk-line, a line-relay at each end of said line, automatic 100 switches controlled by said relays, means for supplying switch operating impulses over said line in one direction, to energize one of said relays, means for supplying switch operating impulses over said line in the opposite direction, to energize the other 105 relay, another trunk conductor, and a local trunk release circuit at each end of said 110 trunk-line.

trunk-line, which circuit includes said last-mentioned trunk conductor.

51. In a telephone exchange system, the combination of a two-way trunk-line, line-relays at opposite ends of said trunk-line, automatic switches controlled by said line-relays, means for using the relays at both ends of the trunk-line when the automatic switch is operated at one end thereof, means for using the relays at both ends of the trunk-line when the automatic switch is operated at the other end thereof, and a local trunk release circuit at each end of said trunk-line.
52. In a telephone exchange system, the combination of a two-way trunk-line, a line-relay at each end of said trunk-line, an automatic switch controlled by one relay, another automatic switch controlled by the other relay, means for causing one relay to control the other relay when the trunk-line is used for trunking in one direction, means for causing the other relay to control the said one relay when the trunk-line is used for trunking in the opposite direction, and a local trunk release circuit at each end of said trunk-line.

53. In a telephone exchange system, the combination of a two-way trunk-line, a pair of line-relays normally bridged across one end of said trunk-line, a pair of line-relays normally bridged across the other end of said trunk-line, an automatic switch controlled by one pair of relays, an automatic switch controlled by the other pair of relays, each automatic switch being provided with means by which it may establish connection from the trunk-line, each end of said trunk-line being provided with means for establishing connection thereto, and a local trunk release circuit at each end of said trunk-line.

54. In a telephone exchange system, the combination of a two-way trunk-line, automatic switches for extending connection from either end of said trunk-line, automatic trunk-selecting switches for extending connection to either end of said trunk-line, another trunk conductor, and a local trunk release circuit at each end of said trunk-line, which circuit includes said last-mentioned trunk conductor.

55. In a telephone exchange system, the combination of a two-way trunk-line, a set of multiple terminals connected with one end of said trunk-line, a set of multiple terminals connected with the other end of said trunk-line, automatic trunk-selecting switches for extending connection to either end of the said trunk-line through the said multiple terminals, means for extending connection from either end of said trunk-line, another trunk conductor, and a local trunk release circuit at each end of said

trunk-line, which circuit includes said last-mentioned trunk conductor.

56. In a telephone exchange system, the combination of a two-way trunk-line, automatic switches for extending connection from either end of said trunk-line, suitable means for extending connection to either end of said trunk-line, said automatic switches common to the subscribers and individual to said trunk-line, another trunk conductor, and a local trunk release circuit at each end of said trunk-line, which circuit includes said last-mentioned trunk conductor.

57. In a telephone exchange system, the combination of a two-way trunk-line, automatic switching machinery for extending connection from either end of said trunk-line, said switching machinery common to the subscribers, automatic switching machinery for extending connection to either end of said trunk-line, another trunk conductor, and a local trunk release circuit at each end of said trunk-line, which circuit includes said last-mentioned trunk conductor.

58. In a telephone exchange system, the combination of a two-way trunk-line, automatic trunk-selecting switch mechanisms for extending connection to either end of said trunk-line, said mechanisms controllable in accordance with a digit of the called number, automatic switch mechanisms common to the subscribers for extending connection from either end of said trunk-line, and a local trunk release circuit at each end of said trunk-line.

59. In a telephone exchange system, the combination of a two-way trunk-line, a pair of relays individual to one end of said line, a pair of relays individual to the other end of said line, automatic means common to the subscribers and controlled by said relays for trunking in opposite directions over said line, and a local trunk release circuit at each end of said trunk-line.

60. In a telephone exchange system, the combination of a two-way trunk-line, automatic switches, repeaters for transmitting switch operating impulses over said line in either direction, and a local trunk release circuit at each end of said trunk-line.

61. In a telephone exchange system, the combination of a two-way trunk-line, automatic switching means for trunking in one direction over said line, automatic switching means for trunking in the opposite direction over the said line, and means controlled from any calling substation, after the desired connection is found, for producing an audible call-signal at the called substation.

62. In a telephone exchange system, the combination of a two-way trunk-line, subscribers' telephone lines, automatic switch-

- ing means for extending connection over said trunk-line to a called telephone line in one direction, automatic switching means for extending connection over said trunk-line to another called telephone line in the opposite direction, and means controlled from any calling substation after the desired connection is found, for producing an audible call-signal at the called substation.
- 10 63. In a telephone exchange system, the combination of a two-way trunk-line, an automatic trunk-selector for automatically trunking over said line in one direction, another automatic trunk-selector for automatically trunking over said line in the opposite direction, and means controlled from any calling substation, after the desired substation is found, for producing an audible call-signal at the called substation.
- 15 64. In a telephone exchange system, the combination of a two-way trunk-line, a repeater for use in trunking over said line in one direction, another repeater for trunking over said line in the opposite direction, automatic switches, means for causing said repeaters to transmit switch operating impulses over said line, and means controlled from any calling substation for producing an audible call-signal at any called substation.
- 20 65. In a telephone exchange system, the combination of a two-way trunk-line, a line-relay at each end of said line, automatic switches controlled by said relays, means for supplying switch operating impulses over said line in one direction, to energize one of said relays, means for supplying switch operating impulses over said line in the opposite direction, to energize the other relay, and means controlled from any calling substation, after the desired connection is found for producing an audible call-signal at the called substation.
- 25 66. In a telephone exchange system, the combination of a two-way trunk-line, line-relays at opposite ends of said trunk-line, automatic switches controlled by said line-relays, means for using the relays at both ends of the trunk-line when the automatic switch is operated at one end thereof, means for using the relays at both ends of the trunk-line when the automatic switch is operated at the other end thereof, and means controlled from any calling substation for producing an audible call-signal at any called substation.
- 30 67. In a telephone exchange system, the combination of a two-way trunk-line, a line-relay at each end of said trunk-line, an automatic switch controlled by one relay, another automatic switch controlled by the other relay, means for causing one relay to control the other relay when the trunk-line is used for trunking in one direction, means for causing the other relay to control the said one relay when the trunk-line is used for trunking in the opposite direction, and means controlled from any calling substation for producing an audible call-signal at any called substation.
- 35 68. In a telephone exchange system, the combination of a two-way trunk-line, a pair of line-relays normally bridged across one end of said trunk-line, a pair of line-relays normally bridged across the other end of said trunk-line, an automatic switch controlled by one pair of relays, an automatic switch controlled by the other pair of relays, each automatic switch being provided with means by which it may establish connection from the trunk-line, each end of said trunk-line being provided with means for establishing connection thereto, and means controlled from any calling substation for producing an audible call-signal at any called substation.
- 40 69. In a telephone exchange system, the combination of a two-way trunk-line, automatic switches for extending connection from either end of said trunk-line, automatic trunk-selecting switches for extending connection to either end of said trunk-line, and means controlled from any calling substation, after the desired connection is found, for producing an audible call-signal at the called substation.
- 45 70. In a telephone exchange system, the combination of a two-way trunk-line, a set of multiple terminals connected with one end of said trunk-line, a set of multiple terminals connected with the other end of said trunk-line, automatic trunk-selecting switches for extending connection to either end of the said trunk-line through the said multiple terminals, means for extending connection from either end of said trunk-line, and means controlled from any calling substation, after the desired connection is forming for producing an audible call-signal at the called substation.
- 50 71. In a telephone exchange system, the combination of a two-way trunk-line, automatic switches for extending connection from either end of said trunk-line, suitable means for extending connection to either end of said trunk-line, said automatic switches common to the subscribers and individual to said trunk-line, and means controlled from any calling substation, after the desired connection is found, for producing an audible call-signal at the called substation.
- 55 72. In a telephone exchange system, the combination of a two-way trunk-line, automatic switching machinery for extending connection from either end of said trunk-line, said switching machinery common to the subscribers, automatic switching ma-

chnery for extending connection to either end of said trunk-line, and means controlled from any calling substation, after the desired connection is found, for producing an 5 audible call-signal at the called substation.

73. In a telephone exchange system, the combination of a two-way trunk-line, automatic trunk-selecting switch mechanisms for extending connection to either end of 10 said trunk-line, automatic trunk-selecting switch mechanisms common to the subscribers for extending connection from either end of said trunk-line, and means controlled from any calling substation, after 15 the desired connection is found, for producing an audible call-signal at the called substation.

74. In a telephone exchange system, the combination of a two-way trunk-line, a pair 20 of relays individual to one end of said line, a pair of relays individual to the other end of said line, automatic means common to the subscribers and controlled by said relays for trunking in opposite directions over 25 said line, and means controlled from any calling substation for producing an audible call-signal at any called substation.

75. In a telephone exchange system, the combination of a two-way trunk-line, automatic switches, repeaters for transmitting switch operating impulses over said line in either direction, and means controlled from any calling substation for producing an audible call-signal at any called substation.

76. In a telephone exchange system, the combination of a two-way trunk-line, automatic means for trunking in one direction over said line, automatic means for trunking in the opposite direction over the said line, 30 a battery having one pole grounded and the other pole normally connected with one end of said trunk-line, and another battery having one pole grounded and the other pole normally connected with the other end of 45 said trunk-line.

77. In a telephone exchange system, the combination of a two-way trunk-line, subscribers' telephone lines, automatic means for extending connection over said trunk-line to a called telephone line in one direction, automatic means for extending connection over said trunk-line to another called telephone line in the opposite direction, a battery having one pole grounded and the other pole normally connected with one end of said trunk-line, and another battery having one pole grounded and the other pole normally connected with the other end of 55 said trunk-line.

78. In a telephone exchange system, the combination of a two-way trunk-line, a selector for automatically trunking over said line in one direction, another selector for automatically trunking over said line in the 65 opposite direction, a battery having one pole

grounded and the other pole normally connected with one end of said trunk-line, and another battery having one pole grounded and the other pole normally connected with the other end of said trunk-line. 70

79. In a telephone exchange system, the combination of a two-way trunk-line, a repeater for use in trunking over said line in one direction, another repeater for trunking over said line in the opposite direction, automatic switches, means for causing said repeaters to transmit switch operating impulses over said line, a battery having one pole grounded and the other pole normally connected with one end of said trunk-line, 75 and another battery having one pole grounded and the other pole normally connected with the other end of said trunk-line.

80. In a telephone exchange system, the combination of a two-way trunk-line, a line-relay at each end of said line, automatic switches controlled by said relay, means for transmitting switch operating impulses over said line in one direction, means for transmitting switch operating impulses over said line in the opposite direction, a battery having one pole grounded and the other pole normally connected with one end of said trunk-line, and another battery having one pole grounded and the other pole normally connected with the other end of said trunk-line. 85

81. In a telephone exchange system, the combination of a two way trunk-line, line-relays at opposite ends of said trunk-line, 100 automatic switches controlled by said line-relays, means for using the relays at both ends of the trunk-line when the automatic switch is operated at one end thereof, means for using the relays at both ends of the 105 trunk-line when the automatic switch is operated at the other end thereof, a battery having one pole grounded and the other pole normally connected with one end of said trunk-line, and another battery having one 110 pole grounded and the other pole normally connected with the other end of said trunk-line.

82. In a telephone exchange system, the combination of a two-way trunk-line, a line-relay at each end of said trunk-line, an automatic switch controlled by one relay, another automatic switch controlled by the other relay, means for causing one relay to control the other relay when the trunk-line 115 is used for trunking in one direction, means for causing the other relay to control the said one relay when the trunk-line is used for trunking in the opposite direction, a battery having one pole grounded and the other pole normally connected with one end of said trunk-line, and another battery having one pole grounded and the other pole normally connected with the other end of 120 said trunk-line.

85. In a telephone exchange system, the combination of a two-way trunk-line, a pair of line-relays normally bridged across one end of said trunk-line, a pair of line-relays 5 normally bridged across the other end of said trunk-line, an automatic switch controlled by one pair of relays, an automatic switch controlled by the other pair of relays, each automatic switch being provided with means by which it may establish connection 10 from the trunk-line, each end of said trunk-line being provided with means for establishing connection thereto, a battery having one pole grounded and the other pole normally connected with one end of said trunk-line, and another battery having one pole grounded and the other pole normally connected with the other end of said trunk-line.
86. In a telephone exchange system, the combination of a two-way trunk-line, automatic switches for extending connection 15 from either end of said trunk-line, automatic switches for extending connection to either end of said trunk-line, a battery having one pole grounded and the other pole normally connected with one end of said trunk-line, and another battery having one pole grounded and the other pole normally connected with the other end of said trunk-line.
87. In a telephone exchange system, the combination of a two-way trunk-line, a set 20 of multiple terminals connected with one end of said trunk-line, a set of multiple terminals connected with the other end of said trunk-line, automatic switches for extending connection to the said trunk-line through the said multiple terminals, means for extending connection from either end of said trunk-line, a battery having one pole grounded and the other pole normally connected with one end of said trunk-line, and another battery having one pole grounded and the other pole normally connected with the other end of said trunk-line.
88. In a telephone exchange system, the combination of a two-way trunk-line, automatic trunk-selecting switch mechanisms 25 for extending connection to either end of said trunk-line, automatic trunk-selecting switch mechanisms for extending connection from either end of said trunk-line, a battery having one pole grounded and the other pole normally connected with one end of said trunk-line, and another battery having one pole 30 grounded and the other pole normally connected with the other end of said trunk-line.
89. In a telephone exchange system, the combination of a two-way trunk-line, a pair of relays individual to one end of said line, a pair of relays individual to the other end of said line, automatic means controlled by 35 said relays for trunking in opposite directions over said line, a battery having one pole grounded and the other pole normally connected with one end of said trunk-line, and another battery having one pole 40 grounded and the other pole normally connected with the other end of said trunk-line.
90. In a telephone exchange system, the combination of a two-way trunk-line, automatic switches, repeaters for transmitting 45 switch operating impulses over said line in either direction, a battery having one pole grounded and the other pole normally connected with one end of said trunk-line, and another battery having one pole grounded and the other pole normally connected with the other end of said trunk-line.
91. In a telephone exchange system, the combination of two exchanges connected by 50 a line terminating at each exchange in a two-way switch, both terminal switches being identical, the said trunk-line and switches forming a combination whereby when the switch at one end of the trunk-line 55 is seized it is made busy and the switch at the other end of the trunk-line is made busy also.
92. In a telephone exchange system, the combination of a two-way trunk switch or 55 repeater dividing a trunk-line at one end into sections, the local section comprising a pair of vertical and rotary conductors, a non-local section of two other vertical and rotary conductors, a condenser separating 60 the local vertical conductor from the non-local rotary trunk-conductor, and a condenser separating the local rotary trunk-conductor from the non-local vertical trunk-conductor.
93. In a telephone exchange system, the combination of a two-way trunk switch and a vertical line-relay normally connected 65 with a non-local vertical trunk-conductor.
94. In a telephone exchange system, the 70

- combination of a two-way trunk switch and a rotary line-relay normally connected with a non-local rotary trunk-conductor.
95. In a telephone exchange system, the combination, in a two-way automatic trunking apparatus, of a vertical switching relay, a vertical line relay, a pair of vertical trunk conductors, and a trunk-release conductor providing an energizing circuit for the vertical switching relay for switching the vertical line relay from one of said vertical trunk conductors to the other.
96. In a telephone exchange system, a two-way automatic trunking apparatus including a trunk conductor, a switching relay for grounding said trunk conductor, and means for controlling said switching relay.
97. In a telephone exchange system, a two-way automatic trunking apparatus including a switching relay, another switching relay for energizing the said first-mentioned switching relay, and means for controlling said second relay.
98. In a telephone exchange system, the combination, in a two-way automatic trunking apparatus, of a vertical line relay, a pair of vertical trunk conductors, a rotary switching relay, a second switching relay for switching the vertical line relay from one of said vertical trunk conductors to the other for grounding one of said vertical trunk conductors, and for energizing the rotary relay, means for controlling said second switching relay, and a rotary relay controlled by said rotary switching relay.
99. In a telephone exchange system, the combination, in a two-way automatic trunking apparatus, of a rotary line relay, a pair of trunk conductors, a rotary switching relay for switching the rotary line relay from one of said trunk conductors to the other, and means for controlling said switching relay.
100. In a telephone exchange system, the combination, in a two-way automatic trunking apparatus, of a vertical trunk conductor, a vertical switching relay for establishing a ground at the vertical trunk conductor, a rotary switching relay for breaking the ground thus established, and means for controlling said relays.
101. In a telephone exchange system, the combination, in a two-way automatic trunking apparatus, of a vertical trunk conductor, a trunk-release conductor, a vertical switching relay, a rotary switching relay, the vertical switching relay energized as soon as the trunk-release conductor is grounded, thereby energizing the rotary switching relay after imparting a momentary preliminary impulse to the vertical trunk conductor, and a rotary relay controlled by said rotary switching relay.
102. In a telephone system, a two-way trunk-line, means for extending connections over said trunk-line from end to end in opposite directions, automatic switches at each end of said trunk for extending connection therefrom, and means responsive to the calling subscriber for releasing the switches at each end of the trunk-line.
103. In a telephone system, a two-way trunk-line, means for extending connections over said trunk-line in opposite directions, automatic switches at each end of said trunk for extending connection therefrom, and means responsive to the called subscriber for releasing the switches at one end of the trunk-line.
104. In a telephone system, a two-way trunk-line, a switch for automatically selecting said trunk-line, one-way trunks also automatically selectable by said switch, another automatic switch for connecting with the other end of said trunk-line, and one-way trunks selectable by said last-mentioned switch, each switch thereby adapted for use in making either local or long distance calls.
105. In a telephone system, a two-way trunk-line, a switch having provisions for selecting said trunk-line, as well as for automatically selecting lines for local connections, and another automatic switch having provisions for connecting with the other end of said trunk-line, as well as for selecting lines for local connections.
106. In a telephone system, a two-way trunk-line, means for trunking in opposite directions over said trunk-line, and a centralized source of ringing current controllable over the trunk-line for signaling the called subscriber.
107. In a telephone system, a two-way trunk-line, means for extending connections over said trunk-line in opposite directions, and centralized instrumentalities controllable over the trunk-line in either direction for projecting ringing current onto the called line to signal the called subscriber.
108. In a telephone system, a two-way trunk-line, suitable instrumentalities for using the trunk-line for calling in either direction, and means controllable over the trunk-line in either direction, by the calling subscriber, for projecting ringing current onto the called line to signal the called subscriber.
109. In a telephone system, a two-way trunk-line, other trunk-lines, and an automatic trunk-selector for selecting said other trunk-lines and individual to said two-way trunk-line, said trunk selector being normally deenergized.
110. In a telephone system, a two-way trunk-line, an automatic trunk-selector for and individual to each end of said trunk-line, and lines to be automatically selected by said selectors, said trunk selectors being normally deenergized.

100

105

110

115

120

125

130

111. In a telephone system, a two-way trunk-line, and an automatic switch individual to said line for extending connection therefrom in accordance with the second 5 digit of the called number. 70
112. In a telephone system, a two-way trunk-line, and an automatic switch for and individual to each end of said trunk-line for extending connection therefrom in accordance with the second digit of the called number. 75
113. In a telephone system, a two-way trunk-line, and automatic switches for use in connection with said trunk-line, for connecting thereto and therefrom in accordance with first and second digits of the called number, said switches normally deenergized and at rest. 80
114. In a telephone system, a two-way trunk-line, and automatic trunk-selectors for use in automatically trunking over said trunk-line in opposite directions, for connecting thereto and therefrom in accordance with first and second digits of the called number, said selectors normally deenergized and at rest. 85
115. In a telephone system, a two-way trunk-line, means including a battery for automatically trunking over said line in one direction, means including another battery for automatically trunking over said line in the opposite direction, and means whereby at least one digit of the called number is called before connection to said trunk is established. 90
116. In a telephone system, a two-way trunk-line, means including a battery for automatically trunking over said line in one direction, means including another battery for automatically trunking over said line in the opposite direction, said batteries having their like poles grounded, and means whereby at least one digit of the called number is called before connection to said trunk is established. 100
117. In a telephone system, a two-way trunk-line, means including one battery for calling over the trunk-line in one direction, means including another battery for calling over the trunk-line in the opposite direction, and means whereby at least one digit of the called number is called before connection to said trunk is established. 110
118. In a telephone system, a two-way trunk-line, means including one battery for calling over the trunk-line in one direction, means including another battery for calling over the trunk-line in the opposite direction, said batteries having their like poles grounded, and means whereby at least one digit of the called number is called before connection to said trunk is established. 120
119. In a telephone exchange system, the combination of a two-way trunk-line, automatic means for trunking in one direction 125
- over the entire length of said line, and automatic means for trunking in the opposite direction over the said line, said means having vertical motion to select a group and then rotary motion to find the said line. 70
120. In a telephone exchange system, the combination of a two-way trunk-line, subscribers' telephone lines, automatic means for extending connection from a calling subscriber's line over said trunk-line to a called subscriber's line in one direction, and automatic means for extending connection from said trunk-line to another called telephone line in the opposite direction, said means having vertical motion to select a group and 80 then rotary motion to find the called line in the predetermined group. 75
121. In a telephone exchange system, the combination of a two-way trunk-line, a selector for automatically trunking over said line in one direction, and another selector for automatically trunking over said line in the opposite direction, each selector having vertical motion and then rotary motion to find said line. 85
122. In a telephone exchange system, the combination of a two-way trunk-line, a repeater for use in trunking over said line in one direction, another repeater for trunking over said line in the opposite direction, automatic switches having vertical and rotary motion to extend connection from the said line, and means for causing said repeaters to transmit switch operating impulses over said line. 90
123. In a telephone exchange system, the combination of a two-way trunk-line, a line relay at each end of said line, automatic switches controlled by said relays, said switches having vertical and rotary motion 105 to extend connection from the said line, means for transmitting switch operating impulses over said line in one direction, and means for transmitting switch operating impulses over said line in the opposite direction. 110
124. In a telephone exchange system, the combination of a two-way trunk-line, line relays at opposite ends of said trunk-line, automatic switches controlled by said line relays, 115 said switches having vertical and rotary motion to extend connection from the said line, means for using the relays at both ends of the trunk-line when the automatic switch is operated at one end thereof, and means 120 for using the relays at both ends of the trunk-line when the automatic switch is operated at the other end thereof.
125. In a telephone exchange system, the combination of a two-way trunk-line, a line 125 relay at each end of said trunk-line, an automatic switch controlled by one relay, another automatic switch controlled by the other relay, said switches having vertical and rotary motion to extend connection from 130

the said line, means for causing one relay to control the other relay when the trunk-line is used for trunking in one direction, and means for causing the other relay to control the said one relay when the trunk-line is used for trunking in the opposite direction.

126. In a telephone exchange system, the combination of a two-way trunk-line, a pair of line relays normally bridged across one end of said trunk-line, a pair of line relays normally bridged across the other end of said trunk-line, an automatic switch controlled by one pair of relays, an automatic switch controlled by the other pair of relays, said switches having vertical and rotary motion to extend connection from the said line, each automatic switch being provided with means by which it may establish connection from the trunk-line, and each end of said trunk-line being provided with means for establishing connection thereto.

127. In a telephone exchange system, the combination of a two-way trunk-line, a pair of relays individual to one end of said line, a pair of relays individual to the other end of said line, and automatic means having vertical and rotary motion controlled by said relays for trunking in opposite directions over said line.

128. In a telephone exchange system, the combination of a two-way trunk-line, automatic switches having vertical and rotary motion, and repeaters for transmitting vertical and rotary switch-operating impulses over said line in either direction.

129. In a telephone system, a two-way trunk-line, automatic switches for extending connections over said trunk-line in opposite directions, having vertical and then rotary motion to extend the connection, and means responsive to the calling subscriber for releasing the switches at each end of the trunk-line.

130. In a telephone system, a two-way trunk-line, automatic switches for extending connections over said trunk-line in opposite directions, having vertical and rotary motion to extend the connection, and means responsive to the called subscriber for releasing the switches at each end of the trunk-line.

131. In a telephone system, a two-way trunk-line, the ends of which line are permanently connected together, a switch for selecting said trunk-line, one-way trunks also selectable by said switch, another automatic switch for connecting with the other end of said trunk-line, and one-way trunks selectable by said last-mentioned switch, each of said switches having vertical and then rotary motion to seize said two-way trunk-line.

132. In a telephone system, a two-way trunk-line, the ends of which line are per-

manently connected together, a switch having provisions for selecting said trunk-line, as well as for selecting lines for local connections, and another automatic switch having provisions for connecting with the other end of said trunk-line, as well as for selecting lines for local connections, each of said switches having vertical and then rotary motion to seize said two-way trunk-line.

133. In a telephone system, a two-way trunk-line, means having vertical and then rotary motion for extending connections over said trunk-line in opposite directions, and centralized instrumentalities controllable over the trunk-line in either direction for projecting ringing current onto the called line to signal the called subscriber.

134. In a telephone system, a two-way trunk-line, the ends of which line are permanently connected together, other trunk-lines, and an automatic trunk-selector having vertical and rotary motion for selecting said other trunk-lines, said selector being individual to said two-way trunk-line.

135. In a telephone system, a two-way trunk-line, an automatic trunk selector for and individual to each end of said trunk-line, having vertical and rotary motion, and lines to be automatically selected by the rotary motion of said selectors.

136. In a telephone system, a two-way trunk-line, the ends of which line are permanently connected together, means including a switch having vertical and then rotary motion and a battery for automatically trunking over said line in one direction, and means including a switch having vertical and then rotary motion and another battery for automatically trunking over said line in the opposite direction.

137. In a telephone system, a two-way trunk-line, the ends of which line are permanently connected together, means including a switch having vertical and then rotary motion and a battery for automatically trunking over said line in one direction, and means including a switch having vertical and then rotary motion and another battery for automatically trunking over said line in the opposite direction, said batteries having their like poles grounded.

138. In a telephone system, a two-way trunk comprising parallel metallic conductors, a single automatic switch for each end thereof, allotted thereto, and means for controlling said switches over the entire length of the trunk to extend connection therefrom.

139. In a telephone system, a two-way trunk comprising parallel metallic conductors adapted necessarily for use only together, means for automatically seizing said trunk at one end to extend a call therover in one direction, means for seizing the other end of the same to extend a call in the opposite direction and means whereby at least

one digit of the called number must be called before connection can be had with said trunk.

140. In a telephone system, a two-way trunk comprising parallel metallic conductors adapted necessarily for use only together, automatic means controllable over the trunk for extending connection from one end thereof, means for extending connection from the other end of the same, and means whereby at least one digit of the called number must be called before connection can be had with said trunk.

141. In a telephone system, a calling device, a trunk line, a second selector responsive to said calling device in accordance with the second digit of the called number when trunking in one direction over said trunk line, and an automatic switch, the said selector provided with a relay for controlling said automatic switch over the trunk line when trunking in the opposite direction.

142. In a telephone system, a calling device, a second selector, a trunk line for and individual to said second selector, said second selector being responsive to said calling device in accordance with the second digit of a called number when trunking in one direction over said trunk, and a connector, said selector provided with a relay for controlling said connector over the trunk line when trunking in the opposite direction.

143. In a telephone system, a calling device, a second selector responsive to said calling device, in accordance with the second digit of the called number, for a call passing through the selector in one direction, and a connector, said selector provided with a relay controlling the operation thereof, said connector responsive to said relay, in accordance with the last two digits of a called number, when a call passes through the selector in the opposite direction.

144. In a telephone system, a calling device, a selector responsive to said calling device, in accordance with the second digit of a called number, when the call passes through the selector in one direction, and provided with a relay responsive to all subsequent digits of a called number when

the call passes through the selector in the opposite direction.

145. In a telephone system, a pair of selectors, each selector provided with a relay controlling the operation thereof, each relay controllable by the other relay.

146. In a telephone exchange system, the combination of a two-way trunk line comprising a pair of metallic conductors, automatic means for trunking over said line in one direction, automatic means for trunking over said line in the opposite direction, and means for applying a guarding potential at each end of said trunk line to protect the said trunk from seizure when the same is used for trunking in either direction.

147. In a telephone exchange system, the combination of a two-way trunk line, automatic means for trunking over said line in one direction, automatic means for trunking over said line in the opposite direction, and means for applying a guarding potential to prevent seizure of said trunk line when the same is used for trunking in either direction.

148. In a telephone exchange system, the combination of a two-way trunk line, automatic means for trunking over said line in one direction, automatic means for trunking over said line in the opposite direction, and means for applying a guarding potential at each end of said trunk line to protect the said trunk from seizure when the same is used for trunking in either direction.

149. In a telephone system, a two-way trunk line, an automatic switch individual to said line for extending connection therefrom in accordance with a digit other than the first digit of the called number.

150. In a telephone system, a two-way trunk line, an automatic switch for and individual to each end of said trunk line for extending connection therefrom in accordance with a digit other than the first digit of the called number.

Signed by me at Chicago, Cook county, Illinois, this 24th day of May, 1906.

TALBOT G. MARTIN.

Witnesses:

EDWARD D. FALES,
B. D. WILLIS.
